FILLING CHUTE FOR ELEVATING BUCKETS

Harold A. Wagner and Gustave H. Wagner,
Portland, Oreg.

Application December 17, 1946, Serial No. 716,694

3 Claims. (Cl. 214—129)

1

Our present invention relates to a material-handling device including a filling chute. The invention is of particular utility in connection with a concrete elevating tower for use in lifting moist concrete to a higher level so as to permit the distribution thereof into forms or the like. The present invention, therefore, comprises a tower having a bucket or the like movable vertically thereon, and a filling chute or a plurality thereof for loading the bucket.

The present invention is illustrated in a combination including a self-propelled vehicle having a tower mounted thereon, the tower being pivotally mounted on the vehicle so as to occupy a horizontal position upon the vehicle while travelling, and movable to a vertical position in its locality of use. Although the invention is of particular utility in such a combination it is to be appreciated that the present invention could be utilized in permanent or semi-permanent installations including a tower adapted to be mounted upon a platform or other support.

The principal object of the present invention is to provide means whereby a concrete elevator bucket may be rapidly loaded with moist concrete.

A further object of the present invention is to provide a construction including a bucket or the like and filling chutes at the sides thereof, the filling chutes being disposed laterally of the edges of the bucket so as not to impede the vertical movement thereof, in combination with filling chute extensions movable to positions overlying the edges of the bucket and to positions laterally of the bucket so as not to impede the vertical movement thereof. In connection with the foregoing the chute extensions are so constructed and arranged with respect to the bucket as to be automatically movable thereby upon elevation of the bucket, and the combination preferably comprises means automatically to retain the chutes in laterally disposed relation so as to permit return of the bucket to loading position, such retaining means being manually releasable and the chutes being thereupon movable to filling position by the effect of gravity.

The objects and advantages of the present invention will be more readily apparent upon inspection of the following specification taken in connection with the accompanying drawings wherein like numerals refer to like parts throughout.

In the drawings Fig. 1 is an end elevation of an automotive vehicle having a tower of the present invention located thereon and showing a bucket in position to be loaded, the filling chutes

and extensions thereof in loading position, and a pair of self-propelled concrete conveyor trucks illustrated in dash outline in the position assumed for discharge of moist concrete or the like into the loading chutes.

Fig. 2 is a partial side elevation of the present invention, partly in section taken substantially from the line 2—2 of Fig. 1;

Fig. 3 is a vertical section taken substantially from the line 3—3 of Fig. 1;

Fig. 4 is a horizontal section taken substantially along the line 4—4 of Fig. 3 and looking in the direction of the arrows;

Fig. 5 is a vertical section taken along the line 5—5 of Fig. 3 looking in the direction of the arrows; and

Fig. 6 is a vertical section taken substantially along the line 6—6 of Fig. 3.

The present invention comprises an automotive vehicle generally indicated by the numeral 10 and including a cab 11 having a window 12 thereon through which the driver of the vehicle may observe the operations taking place at the rear of the vehicle. Details of the automotive vehicle

25 are not important to the present invention.

The rear end of the body 13 of the vehicle has a pair of short vertical posts 15 mounted thereon, one at each corner of the vehicle. The posts 15 are braced by diagonal braces 16 running forwardly toward the front end of the vehicle. A tower, generally indicated by the numeral 20, is pivotally mounted at 17 at the tops of the upright posts 15, the tower being pivotable about the pivots to assume a horizontal position (not shown), or the vertical position illustrated in which it may be held by suitable means 21.

The tower comprises a laterally spaced pair of H-bars 22 and a lateral spaced pair of L-bars 23 forming four corner posts of a substantially rectangular tower, the four posts being spaced and braced by suitable cross members as illustrated. Between adjacent vertical posts 22 and 23 there is provided a vertical L-shaped guiding bar 24 at each side of the tower inside of the bracing extending between posts 22 and 23, with one leg of each guide bar extending inwardly toward the center of the tower. As seen more clearly in Fig. 3 there are braces provided between the rear vertical posts 23 but not between the front vertical posts 22 so that a three-sided column is thus presented.

Preferably the lower ends of each opposed pair of posts 22 and 23 are spanned by a splash guard plate 25 to prevent the splashing of concrete or the like into the central portion of the tower.

When the tower is in vertical position the rear lower portion thereof abuts the rear end of the truck body 13 and is adapted to be latched thereto by suitable means (not illustrated). Various details herein illustrated are illustrative of a preferred embodiment but other details may be substituted therefor.

A carriage 30 is provided with opposed pairs of guide wheels, each pair comprising a lower guide wheel 31, and an upper guide wheel 32, the wheels 31 and 32 extending laterally and being engageable with the opposite faces of the inwardly extending leg of the vertical bar 24, thereby providing means for guiding the carriage 30 in its vertical movement along the tower. Pivots mounted between the opposed side plates 33 of the carriage 30 upon pintles 34 there is provided a bucket 35 adapted to retain a charge of moist concrete or the like therein. The details of the carriage and of the bucket are more particularly illustrated in our co-pending application Serial No. 716,695 and now Patent No. 2,481,266 granted September 6, 1949, filed concurrently herewith, but it is to be appreciated that other forms of carriage and bucket or the like may be substituted for the particular form illustrated.

The top central portion of the back wall of the carriage 30 includes a boss 36 to which is clamped one end of an elevator cable 37 which extends upwardly through the tower about a spaced pair of guide pulleys 38 and 39 on the tower and downwardly to cable winding mechanism (not shown) located in or on the truck and preferably being connectable at will to the engine driving the vehicle 10 by the operator thereof seated in the cab 11. Winding of the cable causes elevation of the carriage and bucket and release thereof causes its descent under the influence of gravity to the bottom of the tower.

The tower is provided with a hopper of any suitable configuration having a chute 41 at its lower end controllable by a gate 42. The hopper may be conveniently mounted upon the tower by means including mounting members 43 shiftable longitudinally of the front corner posts 22. The lower end of the hopper is retained in its position of use by releasable means 44 and the upper end thereof is pivotally mounted upon pintles 45. Upon release of the means 44 the hopper may pivot about the pintles 45 so as to occupy a stowed position inside of the tower 20 so as to permit travel of the vehicle and tower along a road without having a portion thereof projecting high enough to engage bridges or other obstruction.

The bucket 35 is preferably so mounted, the pintles 34 being forwardly of the vertical center line thereof, that its weight and the weight of the material therein will cause it to rest in an upright position and the tower and bucket are preferably provided with cooperating cam means (not shown) the details being illustrated in our co-pending application Serial No. 716,695, filed concurrently herewith, so that the bucket will be automatically dumped upon elevation thereof to a dumping position with relation to the hopper 40 and then will be automatically returned to upright position upon release of the cable 37. Of course, other means may be provided for dumping the bucket into the hopper, such means being immaterial to the present invention.

The present invention comprises means for loading concrete or the like into the bucket 35 from concrete mixers or conveyors such as exemplified by the trucks 50 illustrated in Fig. 1.

To this end each side of the tower is provided with a chute comprising a collecting portion 51 and a pivoted extension 52. The collecting portion 51 preferably comprises an outwardly flaring body having a rim 53 thereabout except at its lower, constricted end. As seen in Fig. 6 the lower end of the portion 51 is pivotally mounted upon a rod 54 mounted in pintle ears 55 and 56 carried by the upright posts 22 and 24 respectively, connection of the portion 51 to the rod 54 being through a plate 57 attached to the bottom surface of the portion 51 and terminating in a rolled edge through which the rod 54 may pass. The portion 51 may be raised to lie closely against the side of the tower for traveling position and may be pivotally swung to its position of use upon the release of suitable latching means (not shown). The collecting portion 51 is retained in downwardly and inwardly inclined position by a retaining chain 58 attached to the rim 53 and to an upright portion of the tower.

The extension portion 52 comprises an open-ended trough having vertical sides 60 adapted to embrace the restricted lower end of the flange 53 and a lower surface forming an extension of the bottom of the portion 51 when in position of use. The portion 52 is pivotally retained in position by the rod 54 which passes through openings in the walls 60. It may be swung to a substantially vertical position as illustrated in Fig. 5, or to a downwardly and inwardly inclined position as illustrated in Fig. 4, being retained in the latter position by a chain 61 extending from a wall 60 to an upright portion of the tower. When in position of use the extension 52 overlies the upper edge of the bucket 35 so that concrete or the like dumped into the collecting portion 51 will be directed into the bucket.

When the bucket is being raised from its lowermost position a cam shoe 65 protruding from an end thereof engages a cam strap 66 extending from the bottom of the extension 52. As soon as the extension has been raised partially toward the position illustrated in Fig. 5, by being lifted by the bucket 35, the shoe 65 will force the extension to pass slightly beyond the position illustrated in Fig. 5 whereupon the shoe will rise above engagement with the strap 66. A cam strap 67 mounted upon side wall 60 is so located as to engage the free end of a latchbar 68 pivoted at 69 upon the tower. The strap 67 has a shoulder portion 70 adapted to assume a substantially vertical position when the extension is raised to the position of Fig. 5 and an end adapted to assume a substantially horizontal position as illustrated in Fig. 5. When the shoe 65 has swum the extension 52 far enough to clear the shoe the latchbar 68 will drop behind the shoulder 70 to retain the extension 52 in its elevated, out-of-the-way position.

The latchbar 68 is attached to one end of a chain 75 extending vertically upward to the outer corner of a crank member 76 pivotally mounted at 77 at the upper end of the vertical post 15. The upper corner of the crank member 76 is attached to a pull rod 78 extending forward to a position adjacent the cab 11 so that the operator of the vehicle or any other person able to reach the rod may pull forwardly thereon to raise the latchbar 68 from engagement with the shoulder 70. The extension 52 when in raised position is in unstable balance so that release of the latching members causes the extension to drop forward to its position of use as illustrated in Fig. 4. Such action is to take place after the

bucket has been returned to the bottom of the tower to receive a succeeding charge of material.

Having illustrated and described a preferred embodiment of our present invention it should be appreciated that modifications in detail and arrangement thereof may be readily achieved. All such modifications as come within the true spirit and scope of the appended claims are considered to be a part of our invention.

What we claim is:

1. An elevator bucket loading device comprising a receiving chute, an extension pivoted at the lower end of said receiving chute and adapted to overlie the edge of the bucket when in operative position and to be swung into inoperative position upon engagement thereof by the bucket when the bucket is being elevated, means to latch said extension in inoperative position to permit return of the bucket comprising a latchbar and a cooperating latch member on said extension, said latch member comprising a cam surfaces operatively engaging said latchbar to raise said latchbar upon upward movement of said bucket and a shoulder behind which said latchbar may drop to hold said extension, and manual means to raise said latchbar from engagement with said latch member.

2. An elevator bucket loading device comprising a receiving chute, an extension pivoted at the lower end of said receiving chute and adapted to overlie the edge of the bucket when in operative position and to be swung into inoperative position upon engagement thereof by the bucket when the bucket is being elevated, means to latch said extension in inoperative position to permit return of the bucket comprising a latchbar and a cooperating latch member on said extension, said latch member comprising a cam surface operatively engaging said latchbar to raise said latchbar upon upward movement of said bucket and a shoulder behind which said latchbar may

drop to hold said extension, a chain attached to said latchbar, and a manual lever for pulling on said chain.

3. An elevator bucket loading device comprising a receiving chute, an extension pivoted at the lower end of said receiving chute and adapted to overlie the edge of the bucket when in operative position and to be swung into inoperative position upon engagement thereof by the bucket when the bucket is being elevated, means to latch said extension in inoperative position to permit return of the bucket comprising a pivoted latchbar and a cooperating latch member on said extension, said latch member comprising a cam surface operatively engaging said latchbar to raise said latchbar upon upward movement of said bucket and a shoulder behind which said latchbar may drop to hold said extension, a chain attached to said latchbar, and a means for pulling on said chain to lift said latchbar from behind said shoulder.
